G. BOISSONNAULT.
TELEPHONE RECEIVER.
APPLICATION FILED JAN. 29, 1921.

1,401,753.

Patented Dec. 27, 1921.

UNITED STATES PATENT OFFICE.

GASTON BOISSONNAULT, OF HEWLETT, NEW YORK.

TELEPHONE RECEIVER.

1,401,753.

Specification of Letters Patent. Patented Dec. 27, 1921.

Application filed January 29, 1921. Serial No. 440,829.

To all whom it may concern:

Be it known that I, GASTON BOISSONNAULT, a subject of the King of Great Britain, and a resident of Hewlett, Long Island, Queens county, and State of New York, have invented certain new and useful Improvements in Telephone-receivers, of which the following is a specification.

This invention relates particularly to receivers of the type used for wireless apparatus. The "head set" ordinarily employed, at times becomes irksome to the operator, particularly after long periods of use, but if removed there is always the danger that a signal or signals will be lost.

One of the objects of my invention is to so construct the head set that when the operator becomes tired, one of the receivers may be removed and quickly converted into a "loud speaking" receiver, audible at a distance from the ear.

A further object is to so construct the parts that the receiver may be as readily reconverted and restored to the head set.

Still further objects are to increase the efficiency of the receiver, particularly as regards its auditory characteristics and to better fit it to the auricle so as to give the operator the full benefit of the greater sensitivity obtained with my improved construction.

In the accompanying drawing I have illustrated the invention embodied in but one of its practical commercial adaptations, but I wish it understood that modifications may be made without departure from the true spirit and scope of the invention as herein-after defined and claimed.

In the drawing referred to: Figure 1 is a view of a head set from which one of the receivers has been removed and

Fig. 2 is a view showing the removed receiver converted into a "loud speaking" instrument.

Fig. 3 is a transverse sectional view on a somewhat enlarged scale of one of the head receivers.

Figs. 4, 5, 6 and 7 are detached sectional views respectively of the sound reflecting disk, the air-chamber ring, one of the spacing washers and the ear piece or auricle fitting member.

Fig. 8 is a side elevation illustrating the receiver as it appears with the ear piece removed and the loud speaking trumpet en-

gaged therewith, said trumpet being broken away and shown in section.

In Figs. 1 and 2 the two receivers 10 and 11 of the head set are shown, one attached to the bracket 12 of the head band 13, and the other removed from its bracket 14 and as having a horn or amplifier 15 attached thereto.

The receivers may be both alike so that the description of one will suffice for the other. The structure will probably be best understood by reference to Fig. 3 wherein it will be seen that the body of the device comprises a casing 16 supporting the magnet 17 and in front of that the diaphragm 18.

At the back of the case and in rear of the magnet I usually provide a sound reflecting wall such as a disk 19 of mica. This appears to reflect or at least to prevent absorption or loss of the minor sound waves.

The sensitiveness of the instrument is further increased, I find, by the provision of a ring-like member, 20, offset in rear of the diaphragm to provide an annular air-chamber 21 at the back of the diaphragm. The effect of this air-chamber apparently is to cushion the movements of the diaphragm in such a way as to increase its responsiveness and there is apparently a co-operative relation between this air-chamber and the sound reflecting wall at the back of the case, because I find that better results are obtained where these elements are combined in the relation shown.

In front of and overlying the diaphragm I have shown an ear piece supporting disk or ring 22 having a central throat or sound outlet in the nature of an outwardly projecting sleeve or collar 23 exteriorly screwed threaded to receive the correspondingly interiorly screw threaded hub 24 of the ear piece 25.

The ear piece may have a convex exposed face 26 as customary with such devices but at the center there is provided a rim or annular lip 27 projecting from the sunken or concave surface to form in effect a nipple to fit into the orifice of the outer ear. This construction is of special advantage in that it assists in excluding external sounds while the receiver is fitted to the ear of the operator and this without discomfort to the wearer.

In the construction disclosed, the ear piece supporting member 22 is formed with a screw flange 28 engaging over a similarly

screw threaded portion of the casing and serves as a means for clamping both the air-chamber ring and the diaphragm over the end of the case one or a suitable number of 5 spacing washers 29 being interposed between the diaphragm and the ring 20 to hold the diaphragm properly spaced from the pole faces of the magnet.

In the present disclosure, the neck of the 10 ear piece supporting member provides the means by which the trumpet amplifier is connected with and supported on the receiver, the change from head receiver to loud speaking receiver being effected, after removal of the receiver from the head band, by simply unscrewing the ear piece from the neck and then screwing the correspondingly threaded end 30 of the trumpet into engagement therewith. The receiver is thus adapted to interchangeably support either the ear piece or the trumpet, the transformation being easily made without disconnecting or breaking any of the electrical connections and without destroying any of the adjustments. When used as a loud speaking receiver, the device may be placed on any convenient support in the horizontal relation shown in Fig. 2.

In making the change from head set to 30 loud speaking receiver, the receiver which is to be used may be slipped out of its holding bracket and the amplifier be substituted for the ear piece thereon while the other or companion receiver is still held to the ear of the operator, this method of use overcoming the possibility of any loss of signals while the transformation is being made. Similarly, the receiver attached to the head band may be used when the trumpet is being 45 removed from the other receiver preparatory to replacement of the ear piece and attachment to the head band.

What I claim is:

1. The combination in a receiver of the 50 class described provided with a supporting neck, of an ear piece and a sound amplifier both detachably and interchangeably engageable with said supporting neck.

2. The combination in a receiver of the

class described provided with a screw threaded supporting neck, of an ear piece and a sound amplifier both detachably and interchangeably engageable with said screw threaded supporting neck, said ear piece and sound amplifier being correspondingly screw threaded to fit the screw threaded portion of the supporting neck.

3. A receiver of the character disclosed 55 provided with a diaphragm and with a support overstanding said diaphragm and having a protruding neck, an ear piece engageable over the neck of said support and a trumpet likewise engageable over the neck of said support in place of said ear piece.

4. A receiver of the character disclosed 60 comprising a case, a magnet in said case, a diaphragm overstanding the poles of said magnet, a support engaged over the diaphragm and having a securing flange engaged with the case, said support having a centrally located throat piece and an ear piece and a loud speaking trumpet interchangeably engageable with said throat.

5. A receiver of the character disclosed 65 provided with a support having a projecting throat piece and an ear piece engaged over said support, said ear piece having a hub portion provided with a raised lip surrounding the throat.

6. In combination, a head band, a pair of 70 receivers supported thereby, one of said receivers being disengageable from the head band independently of the other and provided with means for directly supporting a sound amplifier.

7. In combination, a head band, a pair of 75 receivers supported thereby, one of said receivers being disengageable from the head band independently of the other and provided with means for directly supporting a sound amplifier, and a sound amplifier, said receiver having an ear piece which is engageable with the supporting means and interchangeable with the sound amplifier.

In witness whereof, I have hereunto set 80 my hand this 20th day of January, 1921.

GASTON BOISSONNAULT.
